CLAIM

We claim the ornamental design for an electronic sight, substantially as shown and described.

DESCRIPTION

FIG. 1 is a top, front and left side perspective view of a fully assembled electronic sight showing our new design;

FIG. 2 is a rear elevational view thereof;

FIG. 3 is a front elevational view thereof;

FIG. 4 is a right elevational view thereof;

FIG. 5 is a left elevational view thereof;

FIG. 6 is a top plan view thereof;

FIG. 7 is a bottom plan view thereof; and,

FIG. 8 is an exploded perspective view thereof.

The broken lines are used to show unclaimed environmental structure and form no part of the claimed design.
